ARCHIE H. RIFE AND JAMES R. CARPER, OF DALLAS CITY, ILLINOIS.

CARBURETER.

SPECIFICATION forming part of Letters Patent No. 720,968, dated February 17, 1903.

Application filed June 18, 1902. Serial No. 112,160. (No model.)

To all whom it may concern:

Be it known that we, ARCHIE H. RIFE and JAMES R. CARPER, citizens of the United States, and residents of Dallas City, in the county of 5 Hancock and State of Illinois, have invented new and useful Improvements in Carbureters, of which the following is a full, clear, and exact description.

Our invention relates to carbureters, more 10 particularly of the type used in so-called "vapor-stoves," which burn gasolene and similar hydrocarbons.

Reference is to be had to the accompanying drawings, forming a part of this specification, 15 in which similar characters of reference indicate corresponding parts in all the figures.

Figure 1 is an end elevation, partly in section, of a stove equipped with our invention. Fig. 2 is a fragmentary central section, some- 20 what enlarged, showing certain details of the carbureter proper. Fig. 3 is a plan view, partly in section, of one of the valves for regulating the flow of hydrocarbon; and Fig. 4 is a fragmentary horizontal section upon the 25 line $\alpha\alpha$ of Fig. 2, showing means for operating the valve controlling the supply of air to the mixing-chamber.

The frame 1 of the stove is provided with braces 2 2, a shelf 3, and a top 4, having 30 apertures 5 in the usual manner.

6 is a hood covering the burner 7, which is connected with longitudinal rods 8 and is provided with air-holes 9. Located centrally at the bottom of the burner 7 is a short tube 35 10. The hood 6 is spaced from the burner 7 by means of stays 11 and is connected directly with the air-passage 12, as shown more particularly in Figs. 1 and 2. A smaller tube 13 is connected at its lower end with a sleeve 40 14, provided with horizontal slits 15, constituting a subflame-burner. This sleeve is integrally connected at 16 with a vaporizing-cup 17, the arrangement being such that this 45 cup is heated by the subflame. Within the sleeve 14 and extending centrally across the same is a horizontal rod 18, from which depends a vertical rod 19. Adjustably mounted upon the lower end of this rod is a convex plate 20, provided with air-holes 21 and secured upon the rod 19 by means of an adjustable nut 22. The arrangement is such that

by turning the nut 22 the plate 20 may be raised or lowered slightly, thereby regulating the supply of air to the tube 13.

An exit-pipe 23 is provided for the purpose 55 of carrying off disagreeable odors arising from the burner. This exit-pipe 23 is provided with a series of nipples 24, one of which is shown in Fig. 1, and with a T 25, the arrangement being such that one of the nipples 60 24 projects upwardly, as shown in Fig. 1, into the immediate vicinity of each of the burners.

A hollow pan-like member 26 is pivoted at 27 upon a plate 28, which is in turn secured upon the wall 29 of the stove. The object of 65 this arrangement is to enable the pan-like member 26 to be elevated into the position indicated by dotted lines in Fig. 1 and to be depressed into the position indicated by full lines in said figure. The exit-pipe 23 is pref- 70 erably connected with a chimney, which has of course more or less draft, so that the vapors arising from the burner are covered by the pan-like member drawn through the nipples 24 and carried off to the chimney. 75

The gasolene-tank 30 is provided with a hand-valve 31 and is connected with a pipe 32 in the usual manner. This pipe is provided with a T 33, which leads to all of the 80 burners. From the T 33 a pipe 34 leads to the casing 35, which is connected, preferably integrally, with the tube 36.

A mixing-chamber 37 is provided with hemispherical ends 41 and also with supporting-lugs 40. Inside of this chamber is a vaporizing-plate 38, connected with a cage 39, of gauze, which rests upon the supporting-lugs 40. The object of this arrangement is to provide a large vaporizing-surface. Within the lower hemispherical end 41 are mounted a 90 number of separate wicks 42, made, preferably, of asbestos and supported by a ring 43. A pipe 44, provided with a lip 45, extends obliquely downward from the lower hemispherical end 41 of the mixing-chamber to the vaporizing-cup 17, as indicated more particularly in Fig. 2. When the hydrocarbon liquid is discharged from the tube 36 upon the plate 38, it spreads downward over the gauze cage 39 and is wholly or partially vaporized. 95 Should any portion fail to vaporize, it accumulates in the bottom of the mixing-cham- 100

ber and is thereupon carried up by capillary attraction into the asbestos wicks 42, which of course afford a great extent of surface, and thus facilitate ready vaporization. Should 5 any portion of the hydrocarbon still remain unvaporized, it flows through the tube 44, down into the vaporizing-cup 17, immediately adjacent to the subflame, and is there vaporized.

10 Within the casing 35, near the top of the apparatus, is a cavity 46, with which the pipe 34 is normally in communication. The upper end of this cavity acts as a valve-seat for the jewel-valve 47. This valve is mounted 15 upon the revolute stem 48, which is provided with a thread 49, this thread acting as a bearing upon which is fitted an adjusting-nut 50, which may be used or not, as desired.

The valve-casing 51 is connected by a joint 20 52 to the upper end of the mixing-chamber and is also connected by an elbow 53 to the pipe 12. Within this casing is a revolute valve 54, provided at its upper end with a recess 55. The lower end of the valve-stem 48 25 is provided with an angular portion 56, which is engaged by a bolt 57. The object of this arrangement is to allow the valve-stem 48 to have a slight vertical play, sufficient to compensate for the vertical movement due to the 30 revolution of the threaded portion of the valve-stem in the casing 35.

A clamp 58 is provided with a handle 59 and with a bolt 60, whereby the stem 48 may be rotated by merely manipulating the handle 59.

The general operation of our device is as follows: The tank 30 is wholly or partially filled with gasoline or other hydrocarbon. The handle 59 is turned slightly to the left, 40 thereby lowering the jewel-valve 47 and permitting a slight ingress of hydrocarbon through the tube 36 into the mixing-chamber. The same movement of the handle 59 rotates the valve 54, and thereby opens communication 45 between the mixing-chamber 37 and the air-pipe 12. The degree to which the pipe 34 is opened by the jewel-valve is commensurate with the degree to which the valve 54 opens the air-pipe. The idea is to make the 50 supply of air to the mixing-chamber commensurate with the supply of liquid hydrocarbon thereto. Independently of this action, which is in a sense automatic, however, the handle-valve 37^a (see Figs. 2 and 3) may 55 be adjusted so as to control the supply of liquid through the pipe 36. There is at all times a supply of hydrocarbon vapor in the mixing-chamber 37, for the reason that whenever one or more of the flames are extinguished 60 the vapor remaining in the mixing-chamber is not wasted or allowed to escape, but is retained for future use. It is therefore not necessary for any part of the apparatus to become heated in order that the fire may be 65 lighted. Suppose now that the main flame and the subflame are lighted in the usual

manner. The hood 6 is thereby heated, and of course air is drawn up into the hood and also heated. This air flows in two directions, a part going through the holes 9 to the main 70 burner and another part going through the pipe 12 to the mixing-chamber, where it is admitted with a vapor constantly being formed within said chamber, the ingress of heated air of course volatilizing the liquid hydrocarbon falling upon the plate 38 and spreading over the gauze cage 39. When the flames are extinguished, the burner remains warm for some time; but as the valve 54 is closed no air can enter through the pipe 12. All of 80 the air therefore passes through the holes 9, thereby enabling the burner to cool quite rapidly. As above explained, any odors which may arise from the burners will be carried off by the pipe 23, the more readily if 85 the hood 6 is heated and is thereby caused to promote circulation of air from the vicinity of each burner to the exit-pipe 23.

It is not necessary to close the pipe 44 in any event, for the reason that if the pipe 12 90 is closed by the valve 54 nothing can escape from the mixing-chamber.

It will be noted that the vaporization caused by the carbureter is very complete. There are, in effect, four distinct vaporizing operations, to wit: First, the plate 38 being in immediate proximity to the incoming air and heated thereby will vaporize considerable quantities of the hydrocarbon; secondly, the gauze cage, which is also heated to a greater or less extent, affords an enormous surface likewise tending to promote vaporizing; thirdly, the asbestos wicks acting by capillary attraction perform a somewhat similar office by increasing the surface; fourthly, any liquid hydrocarbon flowing through the tube 44 into the vaporizing-cup 17 is brought to a point immediately adjacent to the subflame, and thereby necessarily vaporized.

We find that this method of vaporizing is 110 very effective and renders the admixture of the air and vapor far more perfect than is attained by many other devices.

It will be observed that our carbureter employs flames which can be instantly ignited 115 and instantly extinguished. It will also be observed that no matter how quickly the valves may be opened or how abruptly the flames may be lighted the admixture of the air and hydrocarbon vapor fed to the flame is 120 always thorough no matter if some time has elapsed since the stove was last used.

Having thus described our invention, we claim as new and desire to secure by Letters Patent—

1. A carbureter, comprising a source of liquid hydrocarbon, a mixing-chamber, a tube connecting the same with said source of liquid hydrocarbon and provided with a revolute valve, a tube for admitting air into said mixing-chamber, said tube being likewise provided with a revolute valve, a revolute stem

- connected with both of said valves, and a handle for actuating said stem, thereby operating said valves simultaneously.
2. A carbureter, comprising a source of liquid hydrocarbon, a mixing-chamber, a tube connecting the same with said source of liquid hydrocarbon, a needle-valve seat mounted upon said tube and provided with a thread, a longitudinal needle - valve engaging said valve-seat and provided with a thread engaging said thread of said valve-seat, said needle being normally free to revolve and to move longitudinally in the direction of its axis, a tube for admitting air to said mixing-chamber, a revoluble valve mounted within said tube, and mechanism connected with both of said valves for actuating the same simultaneously.
3. A carbureter, comprising a mixing-chamber provided with a concave bottom and with supports, a gauze member mounted within said mixing-chamber and resting upon said supports, means for spreading a liquid hydrocarbon upon said gauze member, a plurality of lamp-wicks suspended within said chamber and depending into said concave bottom, and an inlet for admitting air to said mixing-chamber, the arrangement being such that any liquid hydrocarbon which trickles down- ward from said gauze member gathers in said concave bottom and is absorbed by said lamp-wicks.
4. A carbureter, comprising a source of liquid hydrocarbon, a mixing-chamber, a tube connecting the same with said source of liquid hydrocarbon, a needle-valve seat mounted upon said tube and provided with a thread, a longitudinal needle - valve engaging said valve-seat and provided with a thread engaging said thread of said valve-seat, said needle being normally free to revolve and to move longitudinally in the direction of its axis, a tube for admitting air to said mixing-chamber, a revoluble valve mounted within said tube for governing the carrying capacity thereof, mechanism connected with both of said valves for actuating the same, and a movable coupling for permitting said longitudinal movement of said valve.

In testimony whereof we have signed our names to this specification in the presence of two subscribing witnesses.
